UNITED STATES PATENT OFFICE

JOSEPH E. BATIE, OF DETROIT, MICHIGAN, ASSIGNOR TO KELSEY-HAYES WHEEL CORPORATION, OF DETROIT, MICHIGAN, A CORPORATION OF NEW YORK

METHOD OF FORMING BRAKE DRUMS

Application filed October 5, 1925. Serial No. 60,571.

The invention relates to brake drums and has particular reference to brake drums which are designed to be formed from steel having high carbon percentage. The invention has for its main object the improved manufacture of a brake drum by means of which material drawing of the metal is avoided. Other objects of the invention reside in the novel features and sequence of steps as more fully hereinafter set forth.

In the drawings:

Figure 1 is a plan view of a metal blank for forming my brake drum;

Figures 2 and 3 are respectively end and plan views of the blank after the fashioning operation.

Figure 4 is an end view of the blank after it has been hooped.

Figure 5 is a similar view after the blank has been welded and sized;

Figure 6 is a similar view after the blank has been punched;

Figure 7 is a cross section of the completed brake drum secured to a disk.

As shown in Figure 1, 1 is a blank preferably formed of sheet steel having a high carbon percentage, this blank being of indeterminate length. The first step in the operation of forming the brake drum consists in fashioning this blank to form the transversely extending flanges 2 and 3, as shown in Figures 2 and 3. The fashioned blank is then sheared to substantially predetermined length and hooped, as shown in Figure 4, to make from the flanges 2 and 3 respectively, the cylindrical brake flange and the web. As shown in Figure 5, the adjacent ends of the hooped blank are then welded at 4 after which the weld flash is suitably trimmed and the hooped and welded blank then sized to predetermined diameter. This sizing step is preferably accomplished by expanding, by means of which the strength of the weld is decided. The following step consists in punching the web of the brake drum to form the angularly spaced holes 5 through which the means for securing the brake drum to the wheel body

or a disk separate from the wheel body may pass.

If desired the brake drum can be secured to the disk 6 as shown in Figure 7, this disk being separate from the vehicle wheel body and having the central opening 7 for sleeving over the wheel hub. The disk 6 in this instance is preferably provided with a concentric annular shoulder 8 for engagement with the inner edge of the brake drum web to thereby position the brake drum. The brake drum is preferably detachably secured to the disk by suitable means such as the bolts 9 and nuts 10 so that in the event that the brake flange becomes badly worn or damaged the brake drum may be readily removed from the disk and another brake drum secured to the disk.

What I claim as my invention is:

The method of forming a brake drum having a brake flange and a web which includes fashioning a metal blank of indeterminate length to form transversely extending flanges forming the brake flange and web of the brake drum, severing the blank to substantially predetermined length, hooping the blank to form from the transversely extending flanges a cylindrical flange and a transverse inwardly extending flange respectively, welding the ends of the blank to each other, expanding the hooped and welded blank to size and perforating the transverse inwardly extending flange of the blank at angularly spaced points.

In testimony whereof I affix my signature.

JOSEPH E. BATIE.
